UNITED STATES PATENT OFFICE.

BRUNO WESSELMANN, OF HAMBURG, GERMANY.

DOOR-LOCK.

SPECIFICATION forming part of Letters Patent No. 293,548, dated February 12, 1884.

Application filed October 2, 1883. (No model.) Patented in Germany December 9, 1882, No. 23,911.

To all whom it may concern:

Be it known that I, BRUNO WESSELMANN, a subject of the Emperor of Germany, and a resident of Hamburg, in the German Empire, 5 have invented certain new and useful Improvements in Door-Locks, (for which Letters Patent have heretofore been granted to me by the Government of Germany, under date of December 9, 1882, numbered 23,911,) of which the 10 following is a specification.

The invention relates to certain improvements in door-locks, by which the construction of the same is considerably simplified; and the invention consists, first, of the combination, 15 with the spring-bolt, main bolt, and latch, of a spiral spring that is interposed between an extension of the spring-bolt and the tumbler of the main bolt, said tumbler having a downwardly-extending arm that engages the latch, 20 so that thereby the bolts and latch are acted upon by one spring only; and, secondly, of a nut placed on the knob-spindle, and being made of two parts, of an interior portion and an exterior sleeve-shaped portion, which latter is guided by a slot on a guide-stop of the 25 interior portion, between which and a shoulder of the knob-spindle a spiral spring is interposed, that retains by its pressure the inner nut in position when the door is thrown into closed position.

In the accompanying drawings, Figure 1 represents a side elevation of my improved door-lock, shown partly in section, and with the cover removed; and Figs. 2 and 3 are respectively a vertical transverse and horizontal section on lines *x x* and *y y*, Fig. 1.

Similar letters of reference indicate corresponding parts.

A in the drawings represents the casing of 40 my improved door-lock, in which is arranged, one below the other, a spring-bolt, *e*, a main bolt, *h*, and a latch-bolt, *f*. The spring-bolt *e* projects with its beveled end through an aperture of the face-plate of the casing, and is 45 guided in the usual manner by a slot, *e'*, on a fixed transverse pin, *e''*, of the casing. The inner end of the spring-bolt *e* is hinged to projecting ears *a'* of a nut, *a a'*, through the square center hole of which the knob-spindle *b* is 50 passed. A hook-shaped prolongation, *a''*, extends backwardly from the projecting ears of the nut *a*, and is acted upon by a slide-bolt,

c', that is guided in a socket, *c''*, and cushioned by a strong spiral spring, *c*, which is interposed between the slide-bolt *c'* and the bottom 55 of the socket. The outer end of the slide-bolt *c'* is rounded off, so as to move readily along the concave under side of the hook *a''*. The lower end of the socket *c''* is made of conically-tapering shape, and seated in a conical depression of the tumbler *g* of the main bolt, *h*. From the tumbler *g* extends in downward direction an arm, *g'*, that is provided at its lower end with a shoulder, *g''*, which shoulder takes into notches of the latch *f*. In case two or 60 more latches are arranged in a lock, the rod *g'* is extended downwardly and provided with a corresponding number of shoulders, *g''*.

It will be seen that by the arrangement of the spring *c*, slide-bolt *c'*, and its socket *c''* between the spring-nut *a a'* and the tumbler *g* the spring *c* acts on all the three bolts *e*, *h*, and *f* of the lock, according as either one of them is thrown into use. It acts on the spring-bolt *e* by the pressure of the slide-bolt *c'*, and on the 75 main bolt *h* and latch *f* by the pressure of the socket *c''* on the tumbler *g*. The construction of the lock is thereby considerably simplified, as the different springs, which have heretofore been required in connection with the different 80 bolts, are replaced by the single spring *c*.

For the purpose of preventing the turning of the knob-spindle and knobs when the lock is closed by pushing the door into closed position without taking hold of the knob, the nut 85 *a a'* on the spindle is made of two parts—an interior nut, *a*, and an exterior sleeve, *a'*. The exterior sleeve, *a'*, is provided with a slot, *a''*, through which projects a guide-stop, *a''*, that is fixed to the inner nut, *a*, so as to communicate 90 the motion of the knob-spindle to the sleeve *a'*, and thereby to the extension-hook *a''* of the spring-bolt *e*. A spiral spring, *d*, is interposed between the inner nut, *a*, and a shoulder, *b'*, of the knob-spindle *b*, as shown in Fig. 95 2, which spring presses tightly upon the inner nut, *a*, so as to keep the latter in position when the spring-bolt is pushed back into the casing. A on throwing the door into closed position without taking hold of the knob. The spiral 100 spring *d* exerts a frictional pressure upon the interior nut, *a*, which pressure is sufficiently swung to prevent the nut *a* from following the motion of sleeve *a'*, caused by the pushing in

of the spring-bolt *e*. The sleeve *a'* moves thereby freely around the nut *a* until the guide-stop *a³* of the nut *a* arrives at the end of the slot *a⁵* of the sleeve *a'*, and stops thereby the sleeve. When the spring-bolt is moved forward again by the mainspring *c*, the sleeve *a'* moves in opposite direction on the nut *a* until the opposite end of slot *a⁵* arrives at the guide-stop *a³*. When, however, the door is opened or closed by taking hold of and turning the knob, the inner nut, *a*, takes, by its guide-stop *a³*, the sleeve *a'* along, and draws thereby the spring-bolt *e* back in the usual manner.

Having thus described my invention, I claim as new and desire to secure by Letters Patent—

1. The combination of the knob-spindle *b*, nut *a a'*, having ears *a⁴* and extension-hook *a²*, spring-bolt *e*, hinged to the ears *a⁴*, spring-actuated slide-bolt *c'*, guide-socket *c²*, tumbler *g*, having a seat for the guide-socket and a downwardly-extending arm, *g' g²*, main bolt *h*, and latch *f*, substantially as set forth.

2. The combination of the knob-spindle *b*, nut *a a'*, having extension-hook *a²*, spring-bolt *e*, hinged to ears of the nut *a a'*, tumbler *g*, main bolt *h*, and a spring-actuated bolt *c'* and guide-socket *c²*, interposed between the hook *a²* and the tumbler *g*, substantially as set forth. 25

3. The combination of the knob-spindle *b*, 30 interior nut, *a*, placed on said spindle, and having a guide-stop, *a³*, exterior sleeve, *a'*, having a guide-slot, *a⁵*, extension-hook *a²*, and ears *a⁴*, spring-bolt *e*, hinged to the ears *a⁴*, and a spiral spring, *d*, interposed between a shoulder, *b'*, of the spindle and the interior nut, *a*, 35 substantially as set forth.

In testimony that I claim the foregoing as my invention I have signed my name, in presence of two witnesses, this 11th day of September, 1883. 40

BRUNO WESSELMANN.
